(57) **CLAIM**

The ornamental design for a wastegate blanket, as shown and described.

DESCRIPTION

FIG. 1 is a perspective view of a wastegate blanket in a first orientation showing my new design;

FIG. 2 is a front elevation view thereof;

FIG. 3 is a rear elevation view thereof;

FIG. 4 is a left side elevation view thereof;

FIG. 5 is right side elevation view thereof;

FIG. 6 is a top plan view thereof;

FIG. 7 is a bottom plan view thereof;

FIG. 8 is a right side elevation view of the wastegate blanket shown in FIG. 1 in a second orientation; and,

FIG. 9 is a perspective view of the wastegate blanket shown in FIG. 1 positioned on a wastegate of a turbocharger.

The broken line hatching representing a woven material shown across the outer surfaces of the wastegate blanket is part of the claimed design. The shorter spaced broken lines representing internal and external portions of the wastegate blanket form no part of the claimed design.

1 Claim, 9 Drawing Sheets
